UNITED STATES PATENT OFFICE.

FRANCIS EDWARD DAVIES, OF LONDON, ENGLAND.

MACHINE FOR LABELING BOTTLES, TINS, AND LIKE CONTAINERS.

1,146,311.

Specification of Letters Patent. Patented July 13, 1915.

Application filed September 22, 1914. Serial No. 862,968.

To all whom it may concern:

Be it known that I, FRANCIS EDWARD DAVIES, a subject of the King of Great Britain, and resident of 12 Creechurh lane, 5 London, E. C., England, have invented certain new and useful Improvements in Machines for Labeling Bottles, Tins, and like Containers, of which the following is a specification.

10 This invention relates to machines for labeling bottles, tins, and the like, provided with printing, dating or marking devices for producing an indication of identity on the under side of each label prior to its application to the container, and particularly to machines of the kind wherein the labels are removed singly and in succession from an open bottomed magazine containing a packet of labels by means of devices termed "picker plates" which apply gum to the under side of the lowermost label, remove it from the magazine, and bring it into position for application to the container.

According to the present invention the device for producing the indication of identity is carried by the free end of an arm pivotally mounted on a stationary portion of the machine and operatively connected to a tappet rod which extends in the path of motion of 25 a striker carried by one of the picker plates and is so arranged relatively to the picker plates that the arm will be partially rotated, so as to cause the indication to be produced on the label, and then withdrawn to inoperative position prior to the removal of the 30 label by the pickers.

Reference is to be had to the accompanying drawings wherein—

Figures 1 and 2 are respectively a side 40 elevation and an end view of one form of apparatus constructed in accordance with the present invention, showing the picker plates in contact with the lowermost label in the magazine and the type or block carrier in the operative position, while Figs. 3 and 4 are respectively a side elevation and an end view showing the picker plates and type or block carrier in the inoperative position, Figs. 2 and 4 illustrating opposite ends of 45 the apparatus.

a is a type or block carrier provided with an extension *b* engaging in a correspondingly-shaped hole *c* in the free end of a curved arm *d* and held therein by a cross-pin *e* engaging in a slot *f* in said exten-

sion, and *g* is a screw for securing the type or block within the carrier. The arm *d* is provided at the end opposite to that to which the carrier *a* is attached with a pair of lugs *h* and *h'* which are rotatably mounted on a 60 pivot pin *j* carried by a stationary body portion *k* which is shown as secured by means of a removable strap *n* in position by screws *o*, *o* to a rod *m* (shown in dotted lines) forming part of the bottling machine. 65

p is a rod slidably mounted on the body portion *k* and provided on one of its sides with rack teeth *q* with which the teeth of a pinion *r* engage, said pinion being secured to one end of a spindle *s* rotatably mounted in 70 a bearing on the body *k* and carrying on its opposite end a pulley *t*.

u is a chain passing around the pulley *t* and an extension *y* on the lug *h*, one end of said chain being attached at *v* to the pulley 75 *t* while its opposite end is attached at *w* to the extension *y*.

The lower extremity of the rod *p* is screw-threaded and provided with an adjustable stop *z* extending in the path of motion of a 80 striker *5* carried by one of the picker plates *6*, *6'* forming part of the labeling machine.

7 is a spring coiled around the pivot pin *j* and secured at its opposite extremities by means of screws *8* and *9* carried, the one by 85 the body portion *k* and the other by an arm 10 secured to the outer end of the pivot pin, said spring tending to return the arm *d* to inoperative position clear of the path of travel of the picker plate *6*. 90

11 is an adjustable screw serving to limit the extent of the angular motion of the arm *b* in the return direction, said screw being mounted in a slotted aperture *12* and locked in position by means of a set screw *13*. 95

Carried by a spindle *14* mounted to rotate in lugs *15* on the under side of the picker plate *6*, is an inking roller *16* for the type or block. This roller is charged, preferably, with a non-drying ink, in order that the necessity of repeatedly charging the roller may be avoided. The position in which the roller *16* is mounted on the picker plate *6* is such that said roller will ink the type or block both prior to and after each marking operation and thus insure the presence on the roller of a sufficient quantity of ink for the next operation. 100

If desired, a perforating or cutting or other device for producing the indication 110

on the label may be substituted for the type or printing block.

Inasmuch as in machines of the kind referred to the picker plates as a rule merely gum the lateral margins of each label, the identification marks may be readily inspected after the label has been attached to the receptacle or container by cutting the label lengthwise and folding it back.

10 What I claim is:—

1. The combination with a machine for labeling bottles, tins and the like, of apparatus for producing an indication of identity on the under side of each label comprising a carrier for the printing block, identification devices therein, a swinging arm for said carrier, means for pivotally mounting the same upon a stationary portion of the machine, a picker plate and means co-operating therewith for operating said swinging arm, substantially as described.

2. The combination with a machine for labeling bottles, tins and the like, of apparatus for producing an indication of identity on the under side of each label comprising a carrier for the printing block, identification devices therein, a swinging arm for said carrier, a block secured to a stationary portion of the machine to which said arm is pivoted, a reciprocating tappet rod in said block, connections adapting the tappet rod to vibrate said arm and a picker plate provided with a lug adapted to strike said tappet rod and thereby operate said swinging arm substantially as described.

3. The combination with a machine for labeling bottles, tins and the like, of apparatus for producing an indication of iden-

tity on the under side of each label comprising a carrier for the printing block, identification devices therein, a swinging arm for said carrier, a block secured to a stationary portion of the machine to which said arm is pivoted, a reciprocating tappet rod in said block, connections adapting the tappet rod to vibrate said arm, a picker plate, means carried thereby for inking said identification devices, and means connected with the picker plate for moving said tappet rod and thereby cause said arm to swing from inoperative to operative position, substantially as described.

4. The combination with a machine for labeling bottles, tins and the like, of apparatus for producing an indication of identity on the under side of each label comprising a carrier, identification devices adapted to be secured in said carrier, means for inking said devices, a swinging arm for said carrier, a block on a stationary portion of the machine on which said arm is pivoted, a reciprocating rack slidable on said block, a pinion on which said rack operates, means connecting said pinion to said arm whereby said arm may be operated by a movement of said rack, a picker plate, means connected therewith for operating said rack in one direction to move said arm into operative position and a spring for returning said arm to inoperative position, substantially as described.

FRANCIS EDWARD DAVIES.
